UNITED STATES PATENT OFFICE.

WILLIAM C. THORNTON, OF CASTLE ROCK, MISSOURI.

COMBINED FRUIT-CANNER AND WEIGHING-SCALES.

SPECIFICATION forming part of Letters Patent No. 229,204, dated June 22, 1880.

Application filed May 11, 1880. (No model.)

To all whom it may concern:

Be it known that I, WILLIAM C. THORNTON, of Castle Rock, Osage county, and State of Missouri, have invented a new and Improved 55 Fruit-Canner and Weighing-Scales, of which the following is a specification.

The object of this invention is to provide a device by means of which the weighing of canned fruit, vegetables, &c., can be conveniently and quickly effected.

The invention consists of a hollow standard fixed upright on a suitable base and containing a vertically-adjustable bar, on the top of which is fixed a yoke or arch in whose ends 15 spring-actuated vertical plungers are adjusted; and it consists, further, of a pair of counter-scales arranged about the foot of the hollow standard and supporting the revolving disks, upon which disks the cans are to rest when 20 being sealed or weighed.

Figure 1 is a front elevation of the device, partly in section. Fig. 2 is a plan of the same on line *x* *x*, Fig. 1; and Fig. 3 is a cross-section on line *y* *y*, Fig. 2.

Similar letters of reference indicate corresponding parts.

In the drawings, A represents the base of the device supporting the upright hollow standard B, in the cavity of which is the vertically-adjustable bar C, which bar C is held at any desired elevation by the thumb-screw D. On the top of the bar C is fixed the yoke or arch E, about whose socketed ends are passed the vertical plungers F F, that carry 30 on their lower ends the disks a a and have on their upper ends the knobs or handles b b, by means of which they may be conveniently raised.

Within the sockets c c of this arch or yoke 40 E the spiral springs encircle the shanks of the plungers F F, and, bearing on the transverse pins f f, force said plungers F F downward with a constant pressure.

G represents the scales, of which G' is the 45 platform, while the base thereof is identical with the base A of the device.

Resting upon the supports g g of the scales G, and pivoted thereon by their pivots h h, so that they may have a horizontal rotary movement, are the disks H H, provided at their peripheries with radial studs k k, by means of

which the disks H H may be conveniently turned.

In operating this device for canning, the bar C, with its attached arch or yoke E, is adjusted 55 and secured at the proper elevation by the thumb-screw D, the point of adjustment being contingent upon the height of the can or cans to be operated upon.

The blocks m, that are pivoted on the base 60 A, are swung beneath the shoulders of the supports g g, to hold said supports up, and thereby prevent pressure upon the scales G, and the filled can or cans (represented at L) are then placed on the revolving disks H and the plungers F F pressed on the tops or covers of said cans L by the spiral springs d d, so as to hold 65 said covers firmly down. Then any overflowing of the liquid contents of the cans L is wiped from them and the sealing-wax or other sealing substance or material is applied to secure the cover to the can. The operator, by taking hold of the studs k k, turns said can L at will by turning the disk H. The pressure of the plunger F is continued until the sealing material has become hardened sufficiently about 70 the joint of the can and cover, and is then removed. While one can is remaining in position for its sealing-wax to cool another can 75 may be operated upon on the opposite side of the device.

When it is desired to weigh a can and its contents, a suitable weight is placed on the arm n of the scales G, the can on one disk, H, and suitable weights on the other disk, H, the 85 blocks m being first removed from beneath the supports g g and the plungers F F being retracted.

Having thus described my invention, I claim as new and desire to secure by Letters Patent—

1. A combined fruit-canner and weighing-scales, constructed substantially as herein shown and described, consisting of base A, hollow standard B, vertically-adjustable bar C, 95 yoke E, spring-actuated plungers F F, scales G, and pivoted rotary disks H H, as set forth.

2. In a combined fruit-canner and scales, the adjustable bar C and yoke E, in combination, substantially as herein shown and described. 100

3. In a combined fruit-canner and scales, the combination, with the adjustable bar C and

socketed yoke E, of the spring-actuated plungers F F, substantially as herein shown and described.

4. In a combined fruit-canner and scales, the 5 pivoted rotary disks H H, substantially as herein shown and described, whereby the cans are supported and revolved, as set forth.

5. In a combined fruit-canner and scales, the combination, with the standard B, adjustable 10 bar and yoke C E, and rotary disks H H, of

the scales G, substantially as herein shown and described.

6. In a combined fruit-canner and scales, the combination, with the disks H H and scales G, of the supports g g and blocks m m, substantially as and for the purpose set forth. 15

WILLIAM CLARK THORNTON.
